UNITED STATES PATENT OFFICE.

GEORGE P. BRAND, OF NEW YORK, N. Y.

FLANGE-CONTROLLING MECHANISM.

1,187,603.

Specification of Letters Patent. Patented June 20, 1916.

Application filed April 13, 1915. Serial No. 21,163.

To all whom it may concern:

Be it known that I, GEORGE P. BRAND, a citizen of the United States, residing at New York, in the county of New York and State 5 of New York, have invented certain new and useful Improvements in Flange-Controlling Mechanism, of which the following is a specification.

This invention relates to certain new and 10 useful improvements in means for automatically controlling the flanges of a take-up spool in automatic musical instruments and the like, said means being controlled by the note sheet and thus rendering the spool applicable for note sheets of different widths.

The mechanism which controls the flanges serves to set the latter or retain them in fixed 20 position after once adjusted to the width of sheet, and may be controlled from the note sheet in a variety of ways. In devices of this character employing fixed flanges it has been necessary to space such flanges a sufficient distance apart to take in the greatest 25 width of sheet, usually allowing a little space so that the edges of the sheet do not contact with the flanges. Having too much room for the music sheet on the take-up spool between the flanges on large rolls of 30 music causes bad re-winding and inaccurate results because it wanders from side to side and makes it wind loose and the core will shift back and forth. The sheet is thus wound unevenly and the one edge will at 35 times engage the one flange and then the other edge will engage the other flange. The disadvantageous results will be readily understood. Furthermore, where tracking devices are employed in conjunction with take-up spools having fixed flanges, this un- 40 even winding throws a great deal more work on the tracking device and distorts the music and, consequently, unsatisfactory results are attained. My present improvement over- 45 comes these objections. Furthermore, my present improvement insures satisfactory results.

In conjunction with the movable flanges I employ automatically movable sheet controlled means operating in unison therewith. 50 In the present instance I have chosen to show such sheet controlled means in the form of devices engageable with the edges of a note sheet, but it is to be understood that this is but one form of sheet controlled 55 means that may be employed in connection with the movable flanges hereinbefore de-

scribed. I may also employ in conjunction with the note sheet controlled and controlling devices hereinbefore referred to, means for moving the music spool in conjunction 60 with said aforesigned devices, although this latter may sometimes be omitted.

Other objects and advantages of the invention will hereinafter appear and the novel features thereof will be particularly 65 pointed out in the appended claims.

The invention is clearly illustrated in the accompanying drawings, which, with the numerals of reference marked thereon, form a part of this specification, and in which— 70

Figure 1 is a front elevation of my present improvement. Fig. 2 is a rear elevation of the lower portion thereof showing the various pneumatic connections. Fig. 3 is a top plan with the top of the music box and other 75 portions removed. Fig. 4 is a vertical section from front to rear, as on the line 4—4 of Fig. 1, looking in the direction of the arrows. Fig. 5 is an enlarged detail with portions in section, showing one of the edge 80 guides and its support. Fig. 6 is a section on the line 6—6 of Fig. 5, looking in the direction of the arrows. Fig. 7 is a section through the music spool actuating pneumatics. Fig. 8 is an enlarged detail of the 85 cut-out valve in its closed position. Fig. 9 is a similar view showing the parts in position upon rewind. Fig. 10 is a view of the valve looking at the inner face.

Like numerals of reference indicate like 90 parts throughout the different views.

In the accompanying drawings I have shown such parts only of a mechanical musical instrument as pertain directly to the present invention, it being understood that 95 the parts not shown or described may be of any conventional form and connected and arranged to operate in the usual manner.

Referring to the drawings, 1 designates a music spool box, 2 the tracker, 3 the take-up spool, 4 the music spool and 5 the spindles of the latter. The flanges 6 of the take-up spool are movable in the direction of the length of its shaft 7. They are normally forced outward, that is away from the 105 ends of the spool by springs 8. They are designed to be moved inward simultaneously toward each other by the following means. At each end of the music spool box, in this instance shown as at the bottom thereof, I 110 affix a pneumatic 9 and each pneumatic carries upon its movable leaf a rod or arm 10 which

extends upward through a slot in the partition or bottom board 11 of the spool box, as seen best in Fig. 4. The member 10 may be secured in any suitable manner to the 5 pneumatic, one convenient form being shown in Fig. 4. The upper end of each member 10 extends preferably above the shaft 7 of the take-up roll so as to exert its influence at a point above said shaft upon a member 12 which extends downward 10 through a slot 13 in the member 11, as seen clearly in Fig. 4, and is, intermediate its ends, sleeved upon the shaft 7 so as to move freely thereon and to engage against the hub 14 of the adjacent flange 6, as seen in Fig. 1. This member 12 has attached to its upper end in any suitable manner, as by a screw 15, a valve body 16 having a port 17, as seen best in Figs. 5 and 6, and which communicate with a passage 18 terminating in a nipple 19 adapted to be connected by a flexible tube 20 with a nipple or the like 21 mounted in the coupling block 22 which has therethrough a passageway 23 from which 25 extends a nipple 24 which, in turn, is connected by tubing 25 with a passage 26 in a block 27. In the block 27 is a passage 28 connecting the two passages 26 through 30 bleeds 29, as shown in Fig. 7. Leading from the passage 28 is a passage 30 designed to be connected in any well known way to the exhaust mechanism of the instrument, not shown. Leading from passages 31 in the block 27, which are in communication with 35 the passages 26, there extends a tube or connection 32 to a cut-out block 33, and a connection or tube 34 to said block 33. From this cut-out block extends a connection 35 communicating with the interior of one 40 pneumatic 9 and from said block there extends another connection 36 communicating with the other pneumatic 9, all as seen clearly in Fig. 2.

The members 12 after extending through 45 the slots 13 in the board 11 extend horizontally, as seen best in Figs. 1 and 3 at 37, and their adjacent ends are pivotally connected, as at 38, with the opposite ends of a bar 39 pivotally mounted between its 50 ends, as at 40, upon the under side of the member 11, as seen clearly in said Figs. 1 and 3.

The ports 17 in the valve bodies 16, one 55 near each end of the trackerbar, are controlled by the valves 41 pivotally mounted on the said blocks, as at 42, and disposed so as to close over said ports, as seen in Figs. 5 and 6. The valves are extended at right angles to their operative portions just described, as seen at 43, and terminate in edge 60 guides 44 arranged to contact with opposite edges of the note sheet 45, as seen clearly in Fig. 1. A spring 46 is disposed between the portion 43 and the adjacent wall of the 65 valve body or block 16 to normally force the

member 43 in the direction of the arrow seen in Fig. 5 and thus normally keep the valve to its seat over the port to close the same.

The spindles 5 of the music spool 4 are 70 carried by the depending portions 46 and 47 of the U-shaped bars 48 and 49 respectively, which are rigidly secured together to move in unison. The adjacent portions 46 and 47 may be braced, if found necessary, by suitable braces 50, as seen in Fig. 1. The U-shaped members are supported on the uprights 51 which have pins 52 at their upper ends engaged loosely in openings in the adjacent portion of the member 49 and these 75 uprights 51 are mounted at their lower ends on screws or the like 53 held in the ends of the music spool box so as to allow of the necessary movement of these uprights to and from the ends of the box. 80

54 is a spring around the shaft 55 confined between the depending portion 46 and the end of the tubular portion of the spindle rigid with the shaft 55, the shaft and spindle being movable together and the spring compressed by movement of the left-hand spindle to the left to permit the insertion of the roll. 85

56 is a vertical rod pivotally mounted between its ends, as at 57, on some fixed support, its upper end being pivotally connected, as at 58, with a rod 59 adjustably connected with the adjacent portion 46 of the U-shaped member 48 by buttons or the like 60 on said rod upon opposite sides of 90 said portion 46. The lower end of this rod 56 has pivotally connected therewith, as at 61, a horizontally disposed rod 62, the other end of which is connected, as at 63, with the movable member 64 of a pneumatic 65, all 95 as shown clearly in Fig. 1.

The movable member 64 of the pneumatic 65 is connected by the rod 66 with the movable member 67 of a pneumatic 68, as seen 100 in Figs. 1 and 2. The pneumatics 65 and 68 are mounted on the block 27 in any well known way and have in their fixed members 105 openings 69 and 70 which communicate with the passages 31 in the block 27 through the lateral passages 71 and 72 in said block, as 110 seen clearly in Fig. 7.

In order that the edge guides, as well as the flanges may be relieved from contact with the sheet during the re-wind, I provide the following mechanism. 73 is the usual 115 toothed wheel movable to and from the music box to cause the music to travel in one direction or the other. In the position shown in Fig. 1, the parts are in position for playing and the valve 74, which is pivotally 120 mounted at 75, is in its closed position. The upper end of this valve is connected by rod 76 with the hub of the toothed wheel 73, as at 77, in any suitable manner. This valve, 125 when in this position, covers the ports 78 130

and 79, as well as the ports 80 and 81 in the coupling block 33. The valve 74 has upon its inner face two transversely disposed depressions 83 and 84, as seen best in Fig. 10. 5 When the valve is in its closed position, these depressions 83 and 84 communicate with the ports 78 and 80 and 79 and 81 respectively and, consequently, the ports 78 and 80 are in communication with each 10 other and the ports 79 and 81 with each other. When the toothed wheel 73 is moved to the right for re-wind, throwing the pin 85 into engagement with an opening in the lower sprocket wheel, the valve 74 is moved 15 to the right uncovering the ports 78 and 79 but still covering the ports 80 and 81, as shown in Fig. 9, so that there is no passage of air therethrough.

86 is a spring bearing on the valve 74 to 20 hold it to its seat.

The ports 78 and 79 connect respectively with the end pneumatics 9 by means of the connections 35 and 36 hereinbefore described and shown in Fig. 2. The ports 80 and 81 25 connect by tubes or the like 32 and 34 hereinbefore described with the passages 31 in the block 27 also clearly described hereinbefore.

With the parts constructed and arranged 30 substantially as hereinbefore described, the operation, briefly stated, is as follows:— Fig. 1 shows the parts in position to be operated. The roll is in position and upon drawing the note sheet over the trackerbar 35 and fastening it in the usual manner to the take-up spool and starting to play, tension is supplied to all of the pneumatic parts, causing the pneumatics 9 on each side of the box to partially collapse until either or both 40 of the edge guides come against the paper, also carrying the flanges with them. Now, if the edge guide at the right should touch the paper first, the valve 41 controlled thereby will be slightly opened and the pneumatic 9 corresponding with the same will 45 cease to have any power to move the edge guide farther and also reduce the power in pneumatic 68 and give the other pneumatics 9 and 65 on the left full power to continue 50 to collapse as the valve 41 controlling the edge guide mechanism is still closed through the bleed 29 on the left, seen in Fig. 7, thereby causing the sheet to move toward the left and the edge guide on the left to move to 55 ward the right until the said edge guide and sheet meet and the two valves assume a slight open position, thereby holding the flanges to practically the exact width of the sheet, and continuing to hold them in this 60 position until playing ceases and the mechanism is reversed for re-winding.

It is to be noted that when either pneumatic 9 ceases to actuate its corresponding edge guide, the other pneumatic, by reason 65 of the connections hereinbefore described

between the said two pneumatics 9, continues to work and to operate both edge guides, moving them simultaneously in opposite directions until the note sheet is centralized and the flanges brought to their adjusted 70 position in close proximity to the opposite edges of the note sheet.

It will be readily seen that the devices hereinbefore described will readily automatically adapt themselves to sheets of 75 varying widths as the flanges of the take-up spool will be automatically carried toward or away from each other according to the width of the sheet and when once adjusted to proper relation they will be thus maintained in such relative position during playing.

Upon the rewind the ports 78 and 79 are uncovered by reason of the movement of the valve 74 to the right, admitting air into 85 the pneumatics 9, 9, when the springs 8 serve to force the flanges 6 outwardly and with them the edge guides so that not only the flanges but the edge guides are moved out of contact with the edges of the note 90 sheet. At the same time the ports 17 in the members 16 are closed by the valves 41, allowing equal tension to remain in the pneumatics 65 and 68 by reason of the bleeds 29, thereby centralizing said pneumatics 65 and 68 and centralizing the music spool 4 so that the sheet will be delivered to and wound thereon in perfect condition, so it will not be torn or 95 rumpled at the edges which is a very important feature in this class of machines. Furthermore, the sheet will be in perfect condition for use the next time. When the parts are again placed in position for playing, the valve 74 is moved to the left, closing the ports 78 and 79 and putting said ports into communication with the ports 80 and 81 through the depressions 83 and 84 in the valve and restoring all of the parts 100 to their normal position ready for playing. 105

It is to be understood that suitable connection is made between the exhaust mechanism and the bleed chamber 28, as by tube or the like 100.

Modifications in detail may be resorted to 115 without departing from the spirit of the invention or sacrificing any of its advantages.

What is claimed as new is:—

1. In a device of the character described, 120 a spool with relatively movable flanges, and flange moving mechanism controlled by the note sheet.

2. In a device of the character described, 125 a take-up spool having relatively movable flanges, and pneumatic means for moving said flanges controlled by a note sheet.

3. In a device of the character described, 130 a spool having relatively movable flanges, pneumatic means for moving the flanges

and means controlled by a note sheet for controlling the pneumatic means.

4. In a device of the character described, a spool having relatively movable flanges, note sheet controlled means and pneumatic means and connections whereby said flanges and note sheet controlled means are actuated simultaneously.

5. In a device of the character described, 10 a spool having relatively movable flanges, note sheet controlled means and pneumatic means and connections whereby said flanges and note sheet controlled means are actuated simultaneously in opposite directions.

15 6. In a device of the character described, a spool having relatively movable flanges, note sheet controlled means and pneumatic means and connections whereby said flanges and note sheet controlled means are actuated in opposite directions.

20 7. In a device of the character described, a spool having relatively movably mounted flanges, pneumatics and connections and note sheet controlled means coöperating therewith to move said flanges and note sheet controlled means.

25 8. In a device of the character described, relatively movable flanges automatically movable to accommodate sheets of different widths.

30 9. In a device of the character described, relatively movable flanges automatically movable by a note sheet to accommodate sheets of different widths.

35 10. In a device of the character described, a spool having movable flanges, note sheet controlled means, pneumatic means and connections whereby said flanges and note sheet controlled means are actuated simultaneously, and means whereby said flanges and note sheet controlled means are moved out of operative position upon the rewind.

40 11. In a device of the character described, a spool having movable flanges, note sheet controlled means, pneumatic means and connections whereby said flanges and note sheet controlled means are actuated simultaneously in opposite directions, and means whereby said flanges and note sheet controlled means are moved out of operative position upon the rewind.

45 12. In a device of the character described, a spool having movable flanges, note sheet controlled means, pneumatic means and connections whereby said flanges and note sheet controlled means are actuated in opposite directions, and means whereby said flanges and note sheet controlled means are moved out of operative position upon the rewind.

50 13. In a device of the character described, a spool having movably mounted flanges, pneumatics and connections and note sheet controlled means coöperating therewith to move said flanges and note sheet controlled means, and means whereby said flanges and

note sheet controlled means are moved out of operative position upon the rewind.

55 14. In a device of the character described, movable flanges automatically relatively movable to accommodate sheets of different widths, note sheet controlled means, and means whereby said flanges and note sheet controlled means are moved out of operative position upon the rewind. 70

15. In a device of the character described, 75 movable flanges automatically relatively movable by a note sheet to accommodate sheets of different widths, note sheet controlled means, and means whereby said flanges and note sheet controlled means are moved out of operative position upon the rewind. 80

16. In a device of the character described, 85 movable flanges automatically relatively movable by a note sheet to accommodate sheets of different widths, note sheet controlled means, and means whereby said flanges and note sheet controlled means are moved out of contact with the note sheet upon the rewind. 90

17. In a device of the character described, 95 a spool having movable flanges, note sheet controlled means, pneumatic means and connections whereby said flanges and note sheet controlled means are actuated simultaneously, means whereby said flanges and note sheet controlled means are moved out of operative position upon the rewind, and music spool controlling means controlled thereby. 100

18. In a device of the character described, 105 a spool having movable flanges, note sheet controlled means, pneumatic means and connections whereby said flanges and note sheet controlled means are actuated simultaneously, means whereby said flanges and note sheet controlled means are moved out of operative position upon the rewind, music spool controlling means controlled thereby, and means for centralizing said music spool 110 controlling means on the rewind.

19. In a device of the character described, a spool with movable flanges, pneumatic means for moving them, means engageable with the edges of a note sheet for controlling 115 said flanges and in turn controlling said pneumatic means.

20. In a device of the character described, a spool with movable flanges, pneumatic means for moving them, means engageable with the edges of a note sheet for controlling 120 said flanges and in turn controlling said pneumatic means, and means for centralizing the note sheet on the rewind.

21. In a device of the character described, 125 a spool with movable flanges, pneumatic means for moving them, and a combined edge guide and pneumatic-controlling means movable with said flanges.

22. In a device of the character described, 130

a pair of pneumatics, a pair of edge guides, and a spool with movable flanges, said edge guides and flanges controlled from either pneumatic.

5 23. In a device of the character described, a pair of pneumatics, and a pair of edge guides controlled by either pneumatic.

24. In a device of the character described, a pair of pneumatics, a pair of edge guides, 10 a spool with movable flanges, said edge guides and flanges controlled from either pneumatic, and a cut-out operable upon the rewind to control said pneumatics.

25. In a device of the character described, 15 a pair of pneumatics, a pair of edge guides, a spool with movable flanges, said edge guides and flanges controlled from either pneumatic, and cut-out means operable upon the rewind for disengaging the flanges and 20 the rewind from the note sheet.

26. In a device of the character described, a spool with movably mounted flanges, pneumatics and connections for moving said flanges, and edge guides movable with the flange moving means. 25

27. In a device of the character described, a spool with movably mounted flanges, pneumatics and connections for moving said flanges, edge guides movable with the flange moving means, and valves carried by the 30 edge guides and controlling said pneumatics.

28. In a device of the character described, a spool with movable flanges, pneumatics and connections for actuating said flanges, and edge guides and pneumatic controlling 35 means mounted for freedom of movement with the flange moving means.

In testimony whereof I affix my signature.

GEORGE P. BRAND.
